CLAIM

The ornamental design for a retention element for ski boot liner, as shown and described.

DESCRIPTION

FIG. 1 is a top perspective view of a first embodiment of a retention element for ski boot liner;
 FIG. 2 is a bottom perspective view of the retention element for ski boot liner of FIG. 1;
 FIG. 3 is a front view of the retention element for ski boot liner of FIG. 1;
 FIG. 4 is a back view of the retention element for ski boot liner of FIG. 1;

- FIG. 5 is a left side view of the retention element for ski boot liner of FIG. 1;
 FIG. 6 is a right side view of the retention element for ski boot liner of FIG. 1;
 FIG. 7 is a bottom view of the retention element for ski boot liner of FIG. 1;
 FIG. 8 is a top view of the retention element for ski boot liner of FIG. 1;
 FIG. 9 is a top perspective view of a second embodiment of a retention element for ski boot liner;
 FIG. 10 is a bottom perspective view of the retention element for ski boot liner of FIG. 9;
 FIG. 11 is a front view of the retention element for ski boot liner of FIG. 9;
 FIG. 12 is a back view of the retention element for ski boot liner of FIG. 9;
 FIG. 13 is a left side view of the retention element for ski boot liner of FIG. 9;
 FIG. 14 is a right side view of the retention element for ski boot liner of FIG. 9;
 FIG. 15 is a bottom view of the retention element for ski boot liner of FIG. 9;
 FIG. 16 is a top view of the retention element for ski boot liner of FIG. 9;
 FIG. 17 is a top perspective view of a third embodiment of a retention element for ski boot liner;
 FIG. 18 is a bottom perspective view of the retention element for ski boot liner of FIG. 17;
 FIG. 19 is a front view of the retention element for ski boot liner of FIG. 17;
 FIG. 20 is a back view of the retention element for ski boot liner of FIG. 17;
 FIG. 21 is a left side view of the retention element for ski boot liner of FIG. 17;
 FIG. 22 is a right side view of the retention element for ski boot liner of FIG. 17;
 FIG. 23 is a top view of the retention element for ski boot liner of FIG. 17; and
 FIG. 24 is a bottom view of the retention element for ski boot liner of FIG. 17.
 FIG. 25 is a top perspective view of a fourth embodiment of a retention element for ski boot liner;
 FIG. 26 is a bottom perspective view of the retention element for ski boot liner of FIG. 25;
 FIG. 27 is a front view of the retention element for ski boot liner of FIG. 25;
 FIG. 28 is a back view of the retention element for ski boot liner of FIG. 25;
 FIG. 29 is a left side view of the retention element for ski boot liner of FIG. 25;
 FIG. 30 is a right side view of the retention element for ski boot liner of FIG. 25;
 FIG. 31 is a top view of the retention element for ski boot liner of FIG. 25; and,
 FIG. 32 is a bottom view of the retention element for ski boot liner of FIG. 25.
